METHOD OF PREPARING FUR FOR FELTING

Jack D. Sartakoff, Elmhurst, Long Island, N. Y.,
assignor to No-Mercury Felt Corporation, a
corporation of New York

No Drawing. Application December 8, 1936,
Serial No. 114,770

4 Claims. (Cl. 8--21)

The natural furs of rabbits, hares, nutria, muskrat, beaver, and other similar animals have well defined hairs, individually terminating in sharp points of a hard and horny character.

5 In the preparation of such furs for felting, it is the common practice to cut off these sharp points by a so-called "pulling" or "clipping" operation which has heretofore been carried out by manually presenting the fur to the cutting action 10 of rapidly rotating knives, in such manner that the hard, pointed ends are cut off. After the fur has been clipped as stated, the conventional procedure is to carrot the fur by applying there-to an appropriate carrotting solution which is 15 permitted to remain in contact with the fur for a sufficient period to bring about certain physical and chemical reactions, to the end that the fur will properly felt.

Tests which I have made in connection with 20 the preparation of fur for felting, demonstrated that if natural fur was subjected to a singeing treatment without preliminary clipping, unusual and wholly unexpected results were obtainable. In certain of such tests, the singeing referred to 25 was carried out upon natural unclipped fur and was effected by moving an incandescent source of heat or a flame in proximity to the fur, or vice versa, and in such relation thereto that the undesirable tips of the individual hairs were 30 burned away, to remove the sharp hard points which have heretofore been cut off by revolving knives, as stated. I found that these points were efficiently removed with practical uniformity and that the fur thus treated gave very satis- 35 factory results in felting. In some cases I was able to felt such fur without the use of any carrotting solution whatever.

While the theoretical reasons for these phenomena have not been fully formulated, it is suggested, nevertheless, that inasmuch as singeing involves burning, i. e., rapid oxidation, and chemical carrotting also involves an oxidation operation, this may give some indication of the reasons 40 for the results attained. In other words, the singeing of the fur brings about, through burning, a rapid oxidation of the ends of the individual hairs, and an oxidizing effect is communicated through attendant thermal treatment, at least to some extent, to the remaining sound fur, 45 so as to have an oxidizing and partial carrotting effect upon the latter. Be that as it may, I have demonstrated that, when the ends of the hairs are burned away, as stated, I have been able to felt the resulting fur, in some cases, without 50 further carrotting of the same. The best results 55

were obtained, however, when a carrotting solution was employed, although a relatively weak carrot, as compared to prior usage, was found to give excellent felts.

Thus the singeing operation as described, has 5 been found to produce the dual result: it efficiently and economically disposes of the hard points of the fur and also has a very definite effect upon the character of the remainder thereof to render it more feltable. 10

In other tests which I made the fur was first clipped by the conventional mechanical clipping operation and the thus clipped fur was subjected to a singeing operation. In these tests appreciably less singeing was required so as not to 15 unduly burn away the fur body. It was found that the fur thus singed produced a better felt than like furs that had been clipped in the same way and felted without singeing. This clearly demonstrated that the singeing operation has a 20 definite effect upon the fur to render it more feltable. 25

In practically carrying out the method of this invention on unclipped fur, the skins may be conveniently caused to travel along a predetermined path on an endless belt or other appropriate conveyor or may be fed along such path by appropriate feeding devices. As thus fed they are caused to pass in proximity to one or more flames or a source of incandescent heat which 30 acts upon the fur to singe away the hard points of the individual hairs. A group of gas flames, fed from a suitable burner, has afforded a convenient medium for singeing the fur and the amount of such singeing has been satisfactorily 35 controlled by moving the flame closer to or further away from the path of travel of the fur and by varying the speed at which the fur passes through or in proximity to the flame. The adjustment may be such and the flame area so 40 constituted as to result in uniform singeing and to such extent that the hard points of the fur are burned away without undesirable burning of the fur. At the conclusion of the singeing operation, the charred ends of the hair and other 45 waste products of combustion which remain on the fur may be conveniently removed by brushing or blowing them off or in any other suitable way.

After the fur has been singed as described and 50 the waste products of combustion removed therefrom, it is thereafter further prepared for felting in any appropriate way and, as hereinbefore stated, in some cases it may be merely cut from the skin and felted. However, if circumstances 55

require or it is desired to do so for any reason whatsoever, a supplemental carroting solution may be employed before cutting the fur from the skin and felting it. Any approved carroting solution may be used in this connection and I have employed the carroting solution of my Patent No. 2,070,927, dated Feb. 16, 1937, to give highly satisfactory results. My tests have shown that in most cases a supplemental carroting is required to give the best felts, although I find that I may use a considerably weaker chemical carroting solution than is required with corresponding furs which have been subjected merely to mechanical clipping before carroting.

15 The method of this invention should not be confused with so-called depilating processes heretofore suggested for the preparation of fur for use on wearing apparel. This prior procedure sought to selectively remove a certain type of hair from skins while leaving unchanged thereon another kind of hair on the same skin. According to such prior practice attempts were made to remove the so-called "water-hairs" or "master hairs" by burning, plucking or the like without burning, cutting or otherwise changing the remaining finer hairs of the pelt which were to be left on the pelt to be used as fur pieces by garment makers.

20 The present invention seeks to do nothing of the kind, but, as hereinbefore described, the hairs of the pelt are clipped, without discrimination and in a non-selective manner. The hard, horny ends common to both the master hairs and the finer hairs are removed indiscriminately by the

25 singeing operation which I have described, to be

followed by felting, or by carroting and felting. In other words, the purpose of this invention is to produce an entirely different product in an entirely different art. The results sought by this invention are unimportant in the preparation of pelts by singeing as exemplified by the prior art.

5

The foregoing detailed description sets forth the invention in its preferred practical forms but the invention is to be understood as fully commensurate with the appended claims.

10

Having thus fully described the invention, what I claim as new and desire to secure by Letters Patent is:

1. The herein described method which comprises singeing the fur hairs indiscriminately 15 while on the skin to remove the horny tips thereof, thereafter cutting the fur from the skin, and thereafter felting the fur.

2. The herein described method which comprises singeing the fur hairs indiscriminately 20 while on the skin to remove the horny tips thereof, thereafter chemically carroting the fur, thereafter cutting the fur from the skin, and thereafter felting the fur.

3. The herein described method which comprises singeing the fur hairs indiscriminately 25 while on the skin, thereafter cutting the fur from the skin, and thereafter felting the fur.

4. The herein described method which comprises singeing the fur hairs indiscriminately 30 while on the skin, thereafter chemically carroting the fur, thereafter cutting the fur from the skin, and thereafter felting the fur.

JACK D. SARTAKOFF. 35
